Primary Examiner — Karen S Acker*Assistant Examiner* — Wendy Arminio(74) *Attorney, Agent, or Firm* — Terry M. Sanks, Esq.;
Beusse Wolter Sanks & Maire, PLLC(57) **CLAIM**

The ornamental design for a closure for a container cover, as shown and described.

DESCRIPTION

FIG. 1 is a perspective view of a closure for a container cover shown in a position of use on a container cover drawn in broken lines.

FIG. 2 is a side view of the closure for a container cover.

FIG. 3 is a top view of the closure for a container cover.

FIG. 4 is a bottom view of the closure for a container cover; and,

FIG. 5 is a cross sectional side view taken along line 5-5 of FIG. 1.

The broken lines in FIGS. 1 and 5 illustrating a container cover depict environment that forms no part of the claimed design.

1 Claim, 2 Drawing Sheets(56)
